UNITED STATES PATENT OFFICE.

MICHAEL F. C. O'BRIEN, OF LOUISVILLE, KENTUCKY.

TOBACCO-WAGON.

SPECIFICATION forming part of Letters Patent No. 447,546, dated March 3, 1891.

Application filed August 2, 1890. Serial No. 360,760. (No model.)

To all whom it may concern:

Be it known that I, MICHAEL F. C. O'BRIEN, a citizen of the United States, residing at Louisville, in the county of Jefferson and 5 State of Kentucky, have invented certain new and useful Improvements in Hand Tobacco Wagons or Trucks; and I do hereby declare the following to be a full, clear, and exact description of the invention, such as will enable others skilled in the art to which it appertains to 10 make and use the same.

My invention relates to hand-trucks; and it consists in the novel arrangement of and combination of parts, as will be hereinafter 15 more fully described, and pointed out in the claims.

Its object is to provide a strong hand-truck for conveniently loading, unloading, and carrying heavy casks, and hogsheads, and especially 20 tobacco-hogsheads.

Referring to the drawings, Figure 1 is a perspective view of my truck as it appears when holding its load. Fig. 2 is a similar view showing it as it appears when unloading. 25 Similar letters refer to similar parts throughout.

A is the axle-bed.

a a are the axles.

B B are bolsters.

30 a' a' are the wheels.

B' B' are perches bolted to the bottom of the bolsters in sockets of a depth corresponding to their thickness. As the front bolster rests on the axle-bed in order to make the 35 front of the truck higher than the rear for convenience in loading, the perches are bent angularly, as shown, so that their ends may be parallel and rest evenly against the bolsters. To each bolster are bolted on each 40 side at its middle part standards C, rising above the bolsters. Passing through these standards above the bolsters are tie-bolts c, on each of which are hinged loosely two curved bed-pieces C', extending laterally in 45 opposite directions above the bolsters, as shown. Their concave sides are uppermost, and the two pieces together form beds, one on the front and the other on the rear gear of the truck, for the hogsheads or casks. At 50 their outer ends those bed-pieces are supported by stirrups, as will be hereinafter described.

On each side of the truck above the perches are two rectangular weight-bars D, on each of which is slipped and firmly keyed near 55 the rear bolster a balance-weight d. These weight-bars pass through round holes in the bolsters that are large enough to allow them a free rolling motion. On each end of the weight-bars are slipped and firmly keyed 60 two stirrup-standards D', one in front of the bolster and one in rear of it, and connected near their tops by a bolt d', passing through both above the bolster, as shown. This bolt furnishes a support for the outer ends of the 65 hinged bed-pieces C', forming the load-seats, as above set forth. On the outer ends of the weight-bars, projecting through the front bolster and outside the stirrup-standards D', just described, are fitted dogs or latches d², 70 which when the truck is loaded or in position to receive its load rest on a seat e, projecting horizontally from the bottom of the bolster, and which may be made integral with the standard C on the front of the bolster. These 75 dogs are held in that position by a key or catch E, hanging from the outer end of the tie-bolt c, which catch has a projecting pedal e' adapted to be moved conveniently by the foot. 80

Fig. 1 shows the position of the load-seat in my truck when I wish to put a hogshead on it, which I do by backing the lower rear end of the truck against the hogshead and then pulling the hogshead over on the truck. 85

When I desire to unload a hogshead, I put the load-seat in the position shown in Fig. 2 and roll the hogshead off the side of the truck. I do this by pushing the catch E to one side, thereby freeing the dog d² on the opposite 90 side. When this is done, the weight of the load depresses the bed-piece on the side on which the dog is freed, flattening the supporting-stirrup on that side down to the bolster, turning the weight-rod and lifting 95 the weight d on that side, as shown. As soon as the hogshead is rolled off and the seat is relieved of its load, the balance-weight d falls back to its normal position, erecting by force of its weight the stirrup-standards 100 and lifting the seat-piece C' and letting the dog d² fall back to its rest on the seat e, when the catch E is pushed back to a vertical position over it and holds it secure, as before.

The weights *d* are adjusted on the weight-bars *D* at such an angle that when there is no load on the truck the dogs will rest naturally in their seats. When the truck is loaded, 5 they are held there by the catch *E*.

F is the truck-tongue, and *f f* are the tongue-holders.

Instead of weights, as shown, I may use 10 springs to throw the bed-pieces back in place, the essential feature of my invention being the load-bed hinged in the center with suitable means for supporting, lowering, and raising its outer ends.

Having thus described my invention, what 15 I claim is—

1. A hand-truck for hauling hogsheads, having, in combination, an axle-bed resting on the front axle, with a bolster above it, a bolster on the rear axle, perches angularly 20 bent, connecting one bolster with the other on each side of the truck, standards bolted to the front and rear of each bolster and rising above it and connected by tie-bolts, on each of which are hinged two curved bars 25 forming a concave load-seat above each bolster, rectangular weight-bars on each side of the truck, passing through the bolsters, and having on each of them between the bolsters a balance-weight, and also having keyed on 30 each one of them, in front and rear of each bolster, stirrup-standards connected at top by a stirrup-bolt adapted to serve as rests for the outer ends of the hinged load-seats, said weight-rods also having keyed on them in 35 front of the front bolster, outside the stirrup-standards, dogs adapted to rest on a seat pro-

jecting horizontally from the bottom of said bolster and to be held in place by a catch hinged at its upper end on the bolt on which the curved seat-pieces are hinged, which catch 40 has a pedal projecting from its lower part, substantially as set forth, and for the purpose specified.

2. In a truck for hogsheads, the combination, with two angular weight-rods *D*, having 45 keyed on them between the front and rear bolsters of the truck balance-weights *d* and in front and rear of each bolster stirrup-standards *D'*, rising above the bolsters and held together at the top by the stirrup tie-bolts *d'*, and on the outside of the stirrup-standards, in front of the front bolster, dogs 50 *d'*, of the standards *C*, the tie-bolts *c*, the curved seat-pieces *C'*, hinged on the bolt *c* at their inner end and adapted to rest on the 55 stirrup tie-bolts *d'* toward their outer end, the catch *E*, having the pedal *e*, and the dog-seat *e'*, substantially as described, and for the purpose specified.

3. In a truck for hogsheads, a load-seat 60 above the axle, consisting of two curved pieces *C'*, hinged at their inner ends, in combination with means for supporting, lowering, and fixing the outer ends at pleasure, for the purpose specified, and substantially as set forth. 65

In testimony whereof I affix my signature in presence of two witnesses.

MICHAEL F. C. O'BRIEN.
